SHOE FORM

William J. De Witt, Auburn, N. Y., assignor to
Shoe Form Co., Inc., Auburn, N. Y., a corpora-
tion of New York

Application July 10, 1934, Serial No. 734,480

4 Claims. (Cl. 12—128.4)

This invention relates to an improvement in a shoe form and more particularly to a toe form having a prong which, when the form is inserted in a shoe, engages the inner sole thereof and resists the removal of the form from the shoe.

The primary object of this invention is to provide a toe form having flanged side walls, a cross brace connected to the side walls of the form and movable relative thereto and a wire movable with the cross brace being secured at one end to one end of the cross brace having a prong at the other end and bearing intermediate its length against the cross brace midway between the side walls.

Other objects of this invention reside in the manner in which the wire and cross brace are connected, thus in one embodiment the wire and cross brace are integral, and in other embodiments the wire and cross brace are connected by a cross brace which also connects the cross brace to a flanged side wall of the form.

Further objects of this invention will appear from a consideration of the following description and of the drawing which forms a part thereof and in which

Fig. 1 is a bottom plan view and Figs. 2 and 3 are sectional views taken along the lines 2—2 and 3—3 on Fig. 1 of one embodiment of this invention;

Figs. 4, 5 and 6 are similar views of another embodiment, the sections shown in Figs. 5 and 6 being taken along the lines 5—5 and 6—6 on Fig. 4; and

Figs. 7, 8 and 9 are similar views of still another embodiment, the section shown in Figs. 8 and 9 being taken along the lines 8—8 and 9—9 on Fig. 7.

Each embodiment of this invention comprises a toe form having flanged side walls of inherently resilient material 10 and 11 connected by a cross brace 12 attached to the side walls by rivets 13 and 14. The rivet 13 is received in a slot 15 formed in the flanged side wall 10 which permits a pivotal movement of the cross brace 12 to expand or contract the form in the usual well known manner. The embodiments disclosed in the drawing differ from each other in the form of the prong wire and the way in which it is secured to the cross brace 12.

In the embodiment shown in Figs. 1, 2 and 3 the prong wire 20 is an integral extension of the cross brace 12 at the end pivoted to the wall 11 by the rivet 14. The wire 20 extends forwardly from the rivet 14, then backwardly under the cross brace, is curved upwardly and downwardly to form

a loop 21 and terminates in a pointed tip 22. The wire 20 being a part of the cross brace 15 obviously moves in unison with the cross brace. The operator by inserting a finger or tool in the loop 21 raises the tip 22 out of contact with the inner sole of the shoe, swings the cross brace forward or backward as desired, and withdraws the contracted form from the shoe.

The prong wire 30 of the embodiment shown in Figs. 4, 5 and 6 is looped around the shank of the rivet 14. From the rivet 14 it is led forward and then backward over the cross brace, bent forward laterally and backward under the cross brace, curved upwardly and downwardly to form a loop 31 and terminates in a pointed tip 32. The wire as it is bent about the cross brace forms a pocket 33 which receives the cross brace midway between the side walls and yieldably holds it therein. The loop 31 may be used in the same manner as the loop 21 to raise the tip and actuate the cross brace. Since the cross brace is yieldably held in the pocket 33 the prong wire will be moved thereby.

Figs. 7, 8 and 9 illustrate another embodiment of the invention which includes a prong wire 40 looped around the rivet 13. The wire 40 extends parallel to the cross brace 12, is coiled around it, bent upwardly and downwardly to form a loop 41 and terminates in a pointed tip 42. The coils 43 surround the cross brace midway between the side walls and insure that the wire and cross brace move as a unit. The loop 41 may be used, in the same manner as the loop 21 of the embodiment first described, to raise the tip 42, actuate the cross brace 12 and withdraw the form from the shoe.

From the above description of the various embodiments it will be noted that in each the prong wire is movable with and by the cross brace, and is yieldably held thereby with its tip in engagement with the inner sole of a shoe. Furthermore the prong wire of each embodiment includes a loop behind the cross brace by which the tip is raised, the cross brace is actuated and the form may be withdrawn from the shoe.

While certain embodiments of the invention have been shown and described it will be understood that I am not limited thereto and that other embodiments may be made without departing from the spirit and scope of the invention as set forth in the following claims.

I claim:

1. A toe form comprising flanged side walls of inherently resilient material, a cross brace spanning said side walls and movable relative thereto

and means connected to said cross brace at one end thereof and movable thereby, said means terminating in a pointed tip and being in engagement with a portion of the cross brace between the side walls whereby when the form is inserted in a shoe the tip is held by the cross brace in engagement with the inner sole thereof to resist the removal of the form from the shoe.

2. A toe form comprising flanged side walls of inherently resilient material, a cross brace spanning said side walls and movable relative thereto and means connected to said cross brace at one end thereof and movable thereby, said means terminating in a pointed tip which when the form is inserted in a shoe engages the inner sole thereof and resists the removal of the form from the shoe and includes a portion which extends under the cross brace whereby the latter yieldably holds said means in contact with the inner sole.

3. A toe form comprising flanged side walls of inherently resilient material, a cross brace spanning said side walls and movable relative thereto, rivets connecting the ends of said cross brace

to the flanged side walls, and a wire, of which one end is fixed by one of said rivets to a flanged side wall, and the other end forms a prong, said wire being connected intermediate its ends to the cross brace midway between the side walls whereby said prong when the form is inserted in a shoe, is held by the cross brace in contact with the inner sole thereof and resists the removal of the form from the shoe.

4. A toe form comprising flanged side walls of inherently resilient material, a cross brace spanning said side walls and movable relative thereto, rivets connecting the ends of said cross brace to the flanged side walls, and a wire, of which one end is fixed by one of said rivets to a flanged side wall, and the other end forms a prong, said wire being removably connected intermediate its ends to the cross brace midway between the side walls whereby said prong when the form is inserted in a shoe, is held by the cross brace in contact with the inner sole thereof and resists the removal of the form from the shoe.

WILLIAM J. DE WITT.
